ROTOR EQUIPPED AERIAL DEVICE

Paul H. Stanley, Huntingdon Valley, Pa., assignor to Autogiro Company of America, Philadelphia, Pa., a corporation of Delaware

Application May 5, 1944, Serial No. 534,247

11 Claims. (Cl. 244—138)

1
This invention relates to aerial devices and particularly to an aerial device equipped with a bladed rotor arranged to provide for retarded descent of the device when it is released or launched at an elevation, for example, from an aircraft.

Broadly, a number of features of the invention are adaptable to many different purposes, for instance, to parachute-type devices for dropping either cargo or an occupant. Certain specific uses for which the invention is particularly well suited are aerial flares and also aerial bombs, employed for pyrotechnic display purposes, or for warfare.

The type of construction with which the invention is particularly concerned is one in which the rotor blades are pivotally mounted to provide freedom for swinging movement of the blades in a direction generally transverse the mean rotative path of travel.

One of the principal objects of the invention is the provision of mechanism for controlling swinging movements of the blades under certain circumstances and for certain purposes as will further appear.

More specifically, the invention contemplates employment of rotor blades which are pivotally mounted to provide for decrease of rotor blade pitch angle as the blades swing upwardly. This is of importance in facilitating initiation of rotation of the rotor at the time when the device is launched or released from an aircraft. Upon launching, the relative air flow set up by descent of the device causes the blades to swing upwardly on their pivots and thereby decrease the blade pitch angle so that the rotor starts turning, and as rotational speed picks up, the action of centrifugal force on the blades causes them to assume a path of travel defining a shallow cone.

According to the invention, provision is made for controlling the upward swinging movement of the blades and preferably for restricting the upper swinging movement about the pivot means which effect decrease of blade pitch, so as to restrain swinging movement of the blades upwardly into positions of substantial parallelism above the body of the device. This aids in ensuring very rapid acceleration of the rotor.

In the preferred arrangement the rotor blades are constructed and positioned so as to be capable of autorotation, thereby providing for a very low rate of descent of the device.

In accordance with another aspect of the invention, pivot means are also provided for the blades, on which pivot means the blades may be

2
folded in order to facilitate compact stowage of the entire device. The blade movement control arrangements of the invention are advantageously constructed to restrict excessive upward movement of the blades about the folding pivots and thereby ensure that relatively large angular upward swinging movements will take place about the pivot means which provides for concurrent decrease of pitch angle.

10 Still another object of the invention is the provision of a novel means to be employed in the launching of aerial devices of the type hereunder consideration. According to this feature, releasable means are provided for retaining the blades in folded position until after the device has been launched. In this embodiment a cable or similar element is employed, which cable is automatically operative to release the blade holding means when the device has dropped sufficiently to place the cable under tension. This system of launching avoids danger of breakage of the rotor blades or damage to the aircraft, which might otherwise occur if the rotor blades unfolded before the device was entirely clear of the aircraft from which it is launched.

According to another feature of the invention, means are provided to assist or assure unfolding of the rotor blades after the device has been launched. In a preferred construction a common means, such as a strip of resilient material is employed not only to perform this function but also to act as a means restraining excessive upward swinging movements of the blades, as above mentioned.

35 How the foregoing and other objects and advantages are attained will appear more fully from the following description referring to the accompanying drawings in which—

40 Figure 1 is a side elevational view of one embodiment of the invention, the view also including a sectional illustration of a casing in which the entire device is adapted to be housed when the blades are folded;

45 Figure 2 is a fragmentary view of the device of Figure 1, released from its casing and with the blades unfolded and swung upwardly in position for initiating rotation of the rotor;

50 Figure 3 is a plan view of a modified form of rotor blade mounting for a device of the type herein disclosed, the view including the inner end portions only of the rotor blades; and

55 Figure 4 is an elevational view of the mechanism shown in Figure 3.

Referring first to Figure 1, it is assumed that

in this particular embodiment the invention is adapted to an aerial flare which comprises a body 6 which, in this instance, may consist of or enclose the flare material. A fitting 7 at the upper end of the body carries a pair of apertured ears 8-8 cooperating to support a pivot pin 9, on which pivot pin a pair of links 10-10 are mounted, one for each blade 11 of the pair of blades comprising the rotor. Each blade 11 is connected with a link 10 by a second pivot 12.

Blade pivots 12 provide for downward folding of the blades to positions in which they lie adjacent to the body portion 6 and with the blades folded, the entire device is adapted to be received in a housing or casing 13, one end of which may be open for release or discharge at the time of launching by withdrawal of pin 13a.

The blades may be retained in folded position by means of a fastening device, such as the elastic cord indicated at 14 in Figure 1, both ends of the cord being provided with loops, one of which is projected through the other and through which said one loop, a pin 15 may be inserted so as to retain the cord around the folded blades and thus keep them in folded position. It will readily be seen that upon withdrawal of pin 15, the blades are free to swing upwardly to their operative positions, for instance, to the positions indicated in Figure 2. Release of pin 15 is preferably effected by means of a cable 16 which may either be held in the hand of the operator or which, advantageously, is connected as at 17 with the casing 13 for the entire unit.

With an arrangement as just described, the device is adapted to be launched by an operator who merely holds the casing in the proper position to release the device from the end of the casing. When the device falls sufficiently to place the cable 16 under tension the pin 15 is withdrawn from the loop in cord 14 and thereupon cord 14 drops off and the relative air flow set up by virtue of descent of the device causes the blades to swing upwardly and thereafter initiate rotation of the rotor as above mentioned.

To facilitate or assure this action, an elastic element 18, interconnects the root fittings of both blades and is in a condition of tension when the blades are folded as in Figure 1.

It may here be noted that if desired the rotor may be rotatively mounted on the body portion, this arrangement being preferable for many purposes, for instance, where the invention is applied to a device of relatively large mass or when the invention is applied to a man-carrying device. However, as is illustrated in Figures 1 and 2, various features of the invention are also adaptable to a device in which the rotor and the body portion are interconnected to rotate together.

In the embodiment of Figures 1 and 2, therefore, after the device has been launched and the blades have been caused to swing upwardly to positions such as indicated in Figure 2, the air flow across the blades initiates rotation of the entire unit, i. e., the rotor and the body together. According to the arrangement shown, initiation of rotation of the rotor is facilitated by virtue of an angular disposition of the axis of pivot 9. The axis of this pivot, when viewed from above the rotor, forms an acute angle with the longitudinal axis of each blade at the leading side of the blade axis and the outboard side of the pivot axis. Because of this obliquity of the pivot axis the pitch angle of the blades is decreased to a negative value when the blades swing upwardly and this decrease in pitch angle facilitates initiation

of rotation under the influence of the air flow across the blades.

It is advantageous, however, that the upward swinging movement of the blades on the oblique pivot axis be restricted at an angular position appreciably out of parallelism with the vertical axis, and, in the arrangement of Figures 1 and 2 this is accomplished by the same elastic element 18 which is used to assist the unfolding of the blades as mentioned above. This element desirably comprises a strip of sponge rubber material, the ends of the strip being fastened to the root end portions of the blades. This element thus constitutes a cushion device restricting extreme upward movement of the blades when they approach positions of parallelism above the body, as shown in Figure 2. The cushion also serves to absorb shocks at the time of launching the device, when the blades swing upwardly under the action of the air flow. Beyond the foregoing the arrangement of the cushion tends to spread the blades from their uppermost positions and thus aids in bringing the blades downwardly toward their normal operative positions, as rotation commences.

Turning now to the arrangement of Figures 3 and 4, it is here assumed that the invention is adapted to a device for carrying either an occupant, cargo, or an explosive, for instance an aerial bomb. Only the upper end portion of the body is illustrated at 20 in Figure 4. A rotor mounting structure 21 is connected with the upper end of the body portion 20 and serves to house and mount bearings 22-22 which cooperate with a rotative rotor spindle 23 projecting upwardly from the mounting structure 21 to carry a pair of apertured lugs 24-24 which serve to mount a pivot pin 25 on which a pair of blade mounting links 26-26 are adapted to swing upwardly and downwardly.

In Figures 3 and 4 the root end portions of a pair of blades are indicated at 27-27, the direction of rotation being indicated by the arrow R. Each blade 27 is connected with a link 26 by means of a pivot 28. Attention is now called to the fact that, as in the embodiment of Figures 1 and 2, each blade is mounted for upward and downward swinging movement about two pivot axes. Moreover, as before, the outboard pivot axis (28) is preferably arranged perpendicular to the longitudinal axis of the associated blade in order to provide for folding of the blades downwardly to positions adjacent side walls of the elongated body portion, for compact stowage. In Figures 3 and 4 it is also contemplated that the axis of pivot 25, on which both of the blades of the pair are mounted, is obliquely inclined with respect to the longitudinal axis of the blades in the same sense as above described with reference to Figures 1 and 2, to facilitate initiation of rotation.

Blade movement control devices are provided in the embodiment of Figures 3 and 4, including for each blade, complementary cooperating stops 29-30 which act to restrict upward swinging movement of the blade about pivot 28 to a position just a little above the horizontal (when the connecting link 26 is also in horizontal position). Because of the stops 29-30, extensive upward swinging movement of each blade must take place about the oblique pivot axis 25.

Control means are also provided to influence swinging movement about the axis of pivot 25. This mechanism includes linkage constraining

the two links 26 to move in unison. For this purpose, pairs of pivoted links 31 interconnect each blade mounting link 26 with a transverse pin 32, the ends of which pin ride in vertical slots 33 formed in the standards 34, which standards are mounted on and rotate with the rotative hub spindle 23.

Because of the links 31 interconnecting opposite blades, as above described, when the blades swing upwardly through a large angle, they move together, the upward movement being limited by engagement of pin 32 with the upper ends of slots 33. In this uppermost position, in which the pin 32 takes the position indicated at 32a and in which links 31 and blades 27 take the positions indicated at 31a and 27a, the blade axes extend upwardly and outwardly at angles in the neighborhood of the mid-position between horizontal and vertical.

The foregoing construction thus also provides for restricted upward swinging movement of a pair of blades about an oblique pivot axis, whereby to ensure rapid initiation of rotation of the rotor.

In addition to the above the arrangement of Figures 3 and 4 provides freedom for downward swinging movement of the blades 27 to folded positions in which the blades lie parallel to and closely adjacent sides of the elongated body as indicated at 27b.

With respect to the blade pitch angle to be employed, it may be said that appreciable variation is permissible. An appropriate autorotative setting found suitable for the purpose is about 4 or 5 degrees above the no-lift setting with reference to a plane perpendicular to the axis of rotation.

I claim:

1. An aerial device comprising a body portion, a bladed rotor connected with the body portion providing for retarded descent of the device, said rotor incorporating a plurality of blades pivotally mounted for upward and downward swinging movement through a range extending above and below a plane perpendicular to their auto-rotational axis, and mechanism for controlling upward swinging movements of the blades including resilient means interconnecting the blades and normally urging them toward positions approximately perpendicular to the axis of rotation of the rotor.

2. A device in accordance with claim 1 in which each blade is of aeroform section adapted for autorotation and mounted for pivotal swinging movement about an axis providing for decrease of blade pitch as the blade swings upwardly, whereby to facilitate initiation of autorotation of the rotor when the device is launched.

3. An aerial device comprising an elongated body portion, a multi-bladed rotor connected with the body portion at an end thereof and providing for retarded descent of the device, blade mounting pivot means providing for upward and downward blade swinging movement in a direction generally transverse the rotative path, the range of upward movement including a position in which the blades approach parallelism with their rotational axis, and means for restricting the upward movement just short of substantial parallelism.

4. A device in accordance with claim 3 in which said last means comprises a resilient element and adapted to limit extreme upward movement thereof.

5. A device in accordance with claim 3 in which said last means comprises a resilient element

interconnecting the blades and adapted to limit extreme upward movement thereof.

6. An aerial device comprising an elongated body portion, a bladed rotor incorporating a pair of blades, the rotor being mounted on an end of the body portion and providing for retarded descent of the device, pivot means for the blades providing for the downward folding movement of the two blades at the opposite sides of the elongated body and means limiting upward pivotal movement of the blades about said pivot means, the limiting means being arranged to permit the blades to swing upwardly above a position perpendicular to their rotational axis to a position just short of parallelism, but to prevent the blades from swinging into positions of substantial parallelism above the body portion.

10 7. A device in accordance with claim 6 and further including second pivot means for the blades providing for decrease of blade pitch angle when the blades swing upwardly.

15 8. A device in accordance with claim 6 and further including second pivot means for the blades providing for decrease of blade pitch angle when the blades swing upwardly, and means constraining the blades of the pair to swing upwardly to the same extent about said second pivot means.

20 9. An aerial device comprising a body portion, a bladed rotor comprising a pair of pivotally mounted rotor blades mounted on the body portion and providing for retarded descent of the device, the blade mounting pivots including, for each blade, two radially spaced pivot axes providing for upward and downward swinging movement of the blade in a direction generally transverse the mean rotative path of travel thereof, the inboard pivot axis being positioned to provide for decrease of blade pitch with upward swinging movement of the blade, and stop means operative with respect to swinging movement about the outboard pivot axis, said stop means being arranged to inter-engage upon upward swinging movement of the blade beyond a small angle from the horizontal, whereby to ensure that extensive upward swinging movement of the blade will take place about the inboard pivot axis.

25 10. An aerial device comprising an elongated body portion, a bladed rotor mounted at one end of the body portion with its rotational axis approximately coinciding with the longitudinal axis of the body portion to provide for retarded descent of the device, a blade of the rotor being mounted for swinging movement in a direction transverse the mean rotative path through a range extending above and below a plane perpendicular to their rotational axis, and yielding means for restraining the blade as against excessive upward swinging movement.

30 11. An aerial device having a sustaining rotor blade adapted to be air rotated when the device is dropped from a height, means providing for locating said blade in a downwardly folded position, and means urging the blade upwardly from folded position toward a position normal to the rotational axis when the device is dropped, wherein both means permit further upward movement of the blade responsive to relative air flow, and the means urging the blade from folded to its operative position also resists extreme upward movement of the blade.
